UNITED STATES PATENT OFFICE.

GEORGE BOWEN CLEVELAND, OF MOBILE, ALABAMA.

COMBINATION DESK AND FILING CABINET.

Application filed May 20, 1925. Serial No. 31,627.

To all whom it may concern:

Be it known that I, GEORGE BOWEN CLEVELAND, a citizen of the United States, residing at Mobile, in the county of Mobile and State of Alabama, have invented certain new and useful Improvements in Combination Desks and Filing Cabinets; and I do hereby declare the following to be a full, clear, and exact description of the invention, such as will enable others skilled in the art to which it appertains to make and use the same.

The present invention relates to improvements in combination desk and filing cabinet and has for an object to provide in a stenographic or clerk's desk a cabinet arrangement for the preliminary filing of letters or other papers.

Another object of the invention resides in combining both preliminary and permanent filing cases accessible to the clerk or stenographer when pursuing the ordinary routine duties without having to move from the desk to separate and remove filing cases.

The purpose of the invention is to conserve the clerk's time, to provide for convenience in the filing of papers, to lessen the likelihood of loss of papers and to promote at all times a neat appearance in and about the desk.

A further object of the invention is to achieve these results in a compact, cabinet and desk.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a plan view of the improved desk and filing cabinet.

Figure 2 is a front elevation with the cabinet shown in section.

Figure 3 is a section taken on the line 3—3 in Figure 1.

Figure 4 is a central section taken through the desk portion with the lid raised.

Figure 5 is an enlarged fragmentary plan view of one of the folders.

Figure 6 is a perspective view of a folder employed, and

Figure 7 is a vertical section through one

of the filing cabinet sections showing a modified arrangement of division plates. 55

Referring more particularly to the drawings the structure embodies the two pedestals with an intermediate desk portion connecting the same. The pedestals are built up of the side walls 8 and 9 erected upon the bases 10 and 11 and providing at one side the file boxes or file cabinet spaces 12, 13 and 14 and at the other side similar boxes or cabinet spaces 15, 16 and 17. The spaces 12 and 13 are separated by the horizontal partition 18 and are accessible through the inner side doors 19 and 20 hinged as indicated at 21 and 22 respectively to the base 10 and horizontal partition 18. The handles 23 and 24 are useful in pulling the doors open. The doors may be held in the closed position shown in Figure 2 as by frictionally fitting in place or by the use of suitable catches. The ends of the compartments are closed by the walls 25 and 26 running the full height of the pedestals. The cabinet space 13 is separated from the uppermost cabinet space 14 by the horizontal partition 27 and this upper cabinet space 14 is accessible through a top door 28 hinged as shown at 29 to the upper edge of the side wall 8. The inner side of the cabinet space 14 is permanently closed by the stationary wall 30 and the lid 28 is normally kept closed by the clasp 31 secured by appropriate fastenings to the lid 28 and having the downwardly and inwardly offset terminal end 32. 75 80 85

In a similar way horizontal partitions 33 and 34 are arranged in the opposite pedestal for separating the spaces 15, 16 and 17 and doors 35 and 36 are arranged to close the compartments 15 and 16, while a top door 37 with a similar form of catch is used to close the upper compartment 17. 90 95

The table board 38 of the desk portion extends between the two pedestals and rests upon a metal or other cleat 39 secured to the lower edge of the wall boards 30. An extension table board 40 is hinged as at 41 to the edge of the table board 38 and also rests upon the cleat 39. This extension table board 40 may be moved up to the dotted line position shown in Figure 4. The same may receive a typewriter or may be used to perform other forms of clerical work. A back 100 105

wall 42 extends up from the rear end of the table board 38 and a top wall 43 extends forwardly from the upper edge of the back wall 42 forming an enclosed space when the 5 extension table board 40 is in the raised position. An extension top wall 44 is hinged to the top wall 43 as indicated at 45 and a fall board 46 is hinged as indicated at 47 to the free edge of the extension top 10 44. The fall board is provided with an operating handle 48.

In the use of the device the parts are normally in the position shown in Figures 1 and 2 wherein the extension top wall 44 15 extends in horizontal alinement with the main top wall 43 and the fall board 46 extends down to the extension table board 40. A suitable form of lock may be used to hold the parts in this position. The extension 20 top wall 44 overlies the inwardly projecting end 32 of the keepers 31 and thereby prevents access to the compartments 14 and 17 until the desk is opened by insertion of a key carried by the authorized proprietor. 25 The lower compartments may be provided also with separate keys for the doors of the cabinet spaces if this is deemed necessary.

On opening the desk the top wall 44 and fall board 46 are thrown to the position 30 shown in Figure 4 where these parts will form a copy holder for use in connection with the typewriter or they will form a shelf for the placing of letters or other material preparatory to filing. The extension 35 table board 40 may be moved up to the dotted line position to give access to the lower compartments 12, 13 and 15, 16 when letters or other papers are to be filed therein. These spaces may constitute file cabinet 40 spaces for permanently filing letters or other papers, while the top boxes 14 and 17 may be used for preliminary filing; that is for filing the day's letters as the carbon copies 45 of the letters are typewritten and after each day or week the letters may be transferred from the temporary files to the permanent files either in the bottom of the pedestals or in separate file cabinets.

In Figure 3 the partition 27 is shown as 50 provided with a series of perforations 50 adapted to receive the pin or other fastening 51 engaging a similar opening 52 in the angular projecting foot 53 on the follower or division plate 54. There may be a number 55 of these followers or division plates for separating the file box into a number of spaces. These spaces may be alphabetically or numerically arranged and the plates 54 may contain numbers of letters accordingly 60 to facilitate the filing of papers therein. As a follow-up system folders 55 shown in Figures 3 and 5 may be provided for the separating or holding of letters. Along the upper edges of each of these folders appear 65 the numbers consecutively from one to 31

designating the number of days in the month. A clip 56 is used in connection with this table of numbers and engages over the upper edge of the folder. The clip will be conspicuous and can be moved back and forth. For instance the clip is arranged just to the right of the numeral 3 indicating that on the third of the month the letter in this particular file is to be checked over and followed up. Of course the clip might be 75 utilized in connection with the first number to the right thereof instead of to the left or by the number obscured by the clip.

In Figure 7 the side walls of the box and the base are provided with the grooves 57 80 to slidably receive the vertical division plates 58 for dividing the box up into a number of spaces in which the papers are to be filed. These division plates may be marked numerically or alphabetically or 85 otherwise to designate compartments into which the matter is to be filed.

With a cabinet so arranged the sorting of the letters is accomplished as the letters are written and if the letters are not too numerous they may remain in the preliminary file boxes. However, in most cases they will be transferred to the permanent filing cases. The filing of the papers may be done either transversely or longitudinally 95 of the boxes and slideable file drawers may be placed in any of the filing spaces if desired.

The clip 56 is adapted to be slid along the upper edge of the folder to indicate any particular day of the month and the month itself is written or otherwise indicated on the clip itself. Abbreviations, or the full spelling of the months may be used.

It is obvious that various changes and modifications may be made in the details of construction and design of the above specifically described embodiment of this invention without departing from the spirit thereof, such changes and modifications being restricted only by the scope of the following claims.

What is claimed is:—

1. A combination desk and filing cabinet comprising pedestals having under filing spaces with lateral doors to give access thereto and upper file spaces with doors opening on the top of the pedestals, a desk structure supported between said cabinets having movable parts to give access to the lateral doors of the pedestals, keepers on the upper doors of the pedestals, and cover means for the desk engaging in closed position said keepers.

2. A combination desk and filing cabinet comprising pedestals having lower compartment spaces with lateral doors and upper compartment spaces with top doors, a table board extending between said pedestals, an extension table board hinged to swing upwardly from the first named table board to

give access to the lateral doors, and upwardly swinging cover means for the desk.

3. A combination desk and filing cabinet comprising pedestals having lower compartments with lateral doors and upper compartments with top doors, keepers on said top doors, table boards extending between said pedestals, one of said table boards being hinged to the other and movable upwardly

to give access to said lateral doors, back and top boards for said desk, extension top and fall boards hinged together and to said top board and adapted to engage said keepers when closed, said extension top and fall boards adapted to swing upwardly to form a copy holder.

GEORGE BOWEN CLEVELAND.
